ATTORNEY

UNITED STATES PATENT OFFICE.

GAETANO LIPARI, OF SAN JOSE, CALIFORNIA.

TOY.

Application filed May 6, 1924. Serial No. 711,437.

To all whom it may concern:

Be it known that I, GAETANO LIPARI, a subject of the King of Italy, and a resident of San Jose, in the county of Santa Clara and State of California, have invented certain new and useful Improvements in Toys, of which the following is a specification.

This invention relates to a toy having movable parts actuated by air currents.

10 It is one object of the invention to provide an air-current actuated element that can be quickly and cheaply manufactured of paper or any similar inexpensive material.

15 It is another object to provide a device that is so formed and hung as to be readily operated by a slight movement of air.

It is still another object to provide a device in which identical blanks can be used 20 for making elements that will revolve in opposite directions.

In the drawing:

Figure 1 is a perspective illustration of 25 the two blanks formed and ready for assembling.

Figure 2 is a perspective illustration of the assembled device provided with pivots.

Figure 3 is a perspective illustration of another embodiment of the invention.

30 Figure 4 is a side elevation of four of the devices assembled in a standard.

Referring more particularly to the drawing, I show at 1 a single piece of light cardboard or paper, circular in form and cut 35 from circumference to center as at 2, the quarters 3 and 4 of the disc on either side of the cut 2 being bent in opposite directions along the diameter 5 at right angles to cut 2 into the positions shown in a plane at 40 right angles to the remaining half or vane 6.

The part indicated by the same numerals, each with the letter "a" placed in conjunction therewith, is identical in form, shape, and material with the element hereinbefore 45 described, and in the process of assembling is inverted with vane 6^a arranged at right angles to vane 6.

The two elements are now joined as in 50 Figure 2 by placing quarter 4 over quarter 4^a, and quarter 3 over quarter 3^a and securing the same together by means of a suitable adhesive.

At the two ends of the device, and on the 55 axis thereof bisecting the superimposed quarters 3-3^a and 4-4^a are arranged pins

7-7 by means of which the device may be mounted on a standard 8 in any suitable manner as by metal loops 9 set in said support and permitting pins 7 to rotate therein.

Since the vanes 6 and 6^a are at right angles to each other and the device rotates on an axis bisecting the angle between said vanes and at right angles to the planes in which the two vanes lie, it is obvious that 60 the said vanes are presented at angles of forty-five degrees to the air current moving in parallel relation to the said axis. Since the air strikes opposite sides of the two vanes simultaneously the device is easily 65 rotated.

The parts of the embodiment shown in Figure 3 are designated by the same reference characters as used in describing the embodiment above referred to since the 75 parts are identical therewith in form and size, but the quarters 3-4 and 3^a-4^a are bent in a direction opposite to those in Figures 1 and 2 and consequently the angular position of vanes 6-6^a relative to the air 80 current is reversed and the device rotates in the opposite direction.

These two oppositely rotating devices are designated as a whole by the letters "A" and "B" respectively, and I have shown two 85 of each mounted to rotate in orifices 9 in support 8 as shown.

It is to be understood, of course, that while I have herein shown and described the preferred embodiment of my invention, 90 changes in form, construction and method of operation may be made within the scope of the appended claim.

I claim:

An article of manufacture comprising two 95 symmetrical vanes, each vane comprising a circular element cut at one place from circumference to center and having the two quarters of the element on either side of said cut bent in opposite directions at right angles to the remaining half of the element, the two vanes being arranged in opposed relation to each other and at right angles to each other with the angularly bent quarters of one element overlapping the opposing 100 angularly bent quarters of the other element, the overlapping quarters being secured together and having pivot pins mounted therein on the axis bisecting the same.

GAETANO LIPARI.
